(57) **CLAIM**

The ornamental design for a table base, as shown and described.

DESCRIPTION

FIG. 1 is a perspective view of a table base showing my new design; and,

FIG. 2 is a top view thereof.

The broken lines illustrate environmental structure and form no part of the claimed design.

Those portions of the table base not shown in the figures form no part of the claimed design.

1 Claim, 2 Drawing Sheets
